UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed January 28, 1925. Serial No. 5,212.

This invention relates to improvements in typewriting machines of the continuous billing or fan-fold type disclosed in the Wernery & Smith Patent No. 1,132,055, dated March 16, 1915, and more particularly the invention relates to means to accommodate a plurality of sets of work-webs which may be typed individually.

Machines have been provided to accommodate separate work-webs, but this has usually required considerable change in structure, and in some instances more space.

An object of the present invention is to adapt the Underwood continuous billing machine to this kind of work with a minimum of change in construction and without requiring additional space.

In carrying out the invention, separate carbon-carriers are provided for each set of webs, and these carbon-carriers are detachably supported on the steps which usually carry carbon-carrying blades in said Wernery & Smith patent. There may be two, three or four webs in the machine, usually only one of them being typed at a time. The webs which are not in use may be folded back between the carbon-carriers, so as not to interfere with manipulation of the active web.

Each carbon-carrier is composed of two blocks, one at each side, said blocks being connected to each other by a bridge or cross-bar. Each block may be composed of one or more steps upon which suitable carbon-carrying blades are detachably mounted. Each carbon-carrier is provided with means for detachably mounting it on the carbon-carrier truck. To this end there are provided resilient devices, which are herein shown on the carbon-carrier, to engage the truck in a suitable manner to hold the carbon-carrier against accidental removal. In one form of the invention these devices are in the nature of split pins on the carbon-carrier to engage in holes in said truck, whereby each carbon-carrier may be readily detached from the truck for the substitution of another set of webs and its individual carbon-carrier.

The carbon-carriers may vary in size, their capacity being determined by the number of steps. They may be arranged in any desired order on the steps of the truck, and the

one associated with the web used most frequently may be arranged at the top of the set.

In another form of the invention there are provided a main carbon-carrier and another carbon-carrier detachably mounted thereon. Each of said carbon-carriers is provided with a series of steps upon which the carbon-carrying blades are supported. The carbon-carriers are also arranged in stepped relation with respect to each other. With this arrangement the detachable carbon-carrier may be used for a separate web independently of the web associated with the main carbon-carrier, or it may be used to increase the capacity of the main carbon-carrier.

To attach the carbon-carrier of the last-named form of the invention, it is provided with two arms, each arm being bifurcated to form two resilient fingers to spring over a stud or screw on the main carbon-carrier. Said screws may be used to secure in place suitable side gages co-operating with the webs.

Other features and advantages will hereinafter appear.

In the accompanying drawings, Figure 1 is a diagrammatic side view in elevation, showing one of the webs in its active position around the platen of the machine, and showing also the inactive webs folded back between the carbon-carriers.

Figure 2 is an alternative arrangement of the carbon-carriers.

Figure 3 is a modification of the auxiliary carbon-carriers illustrated in Figures 1 and 2.

Figure 4 is a perspective view of the modified carbon-carrier.

Figure 5 is a perspective view of the carbon-carriers illustrated in Figure 1.

Figure 6 is a fractional perspective view of a six-blade carbon-carrier, illustrating the method of attaching the same to the regular carrier, and showing the carbon-carrying blades.

The fan-fold typewriting machine comprises a carriage upon which there is revolvably mounted a platen 10 displaceable forwardly away from its co-operating feed-rolls 11 and 12, to straighten out work-webs normally fed around the platen and typed upon

by the type-bars 13 in front thereof. At the rear end of the platen there is provided a frame forming part of the carriage and supported at its rearmost end by a cross-bar 5 fast to the frame of the machine. The rear frame comprises rails 14 upon which a carbon-carriage 15 is slidably mounted on wheels 16 pivoted on said carbon-carriage.

There may be plurality of webs on the machine, each of the webs having a plurality of plies, and the plies being interleaved by sheets of carbon-paper. However, only one of the webs may be typed upon at one time, and while typing upon one the other webs 53 are folded back between the carbon-carrying blades.

The active web is indicated by the numeral 17 in Figure 1, and is shown over a cross-bar 18 between guides 19 and is passed over the carbon-carriage by interleaving the plies 20 of the web with sheets of carbon-paper 21 having their rear ends fast to carbon-carrying blades 22. The leading edge of the web is pulled forward over a rear table 23, down and under the platen to engage with the feed-rolls, and up around the platen over a front table, not shown.

When it is desired to write upon any other web, the active web is then withdrawn from engagement with the platen and is folded back as shown in Figure 2, in which another web 24 is shown threaded between the carbons and around the platen.

One of the features of this invention is the provision of means whereby webs containing a different number of plies may be used on a standard machine having a single carbon-carrier and truck, and to this end there is provided a plurality of auxiliary carbon-carriers which may be attached to the regular carrier disposed to carry any number of carbon blades to suit the number of plies of the web. In one form of this invention the auxiliary carbon-carriers, as shown in Figures 1, 2, 5 and 6, are attached to the regular carbon-carriers 25 by means of split pins 26 fitting into the holes 27 which normally hold the carbon-blades. Although there are provided two pins at each end for holding the auxiliary carbon-carriers on the regular carbon-carrier, it is obvious that one at each end would also effectively hold the carriers in place, due to the cross-bar connecting the two end blocks. In Figure 5 the auxiliary carbon-carriers are illustrated of different capacities, that is to say, for carrying either two, four or six carbon-sheets, and all being interchangeable with one another; so that the web which is used more often may be placed at the top, where it is handier to operate. In removing any of the auxiliary carriers from the truck for substitution of another set of webs, it will be noted that the carbon-blades associated with any set always remain rigid

in working position with relation to one another. This facilitates removal and attachment of different web sets by reason of the fact that the group of carbons and blades used with each web set is always properly held in place. A carbon-carrier in its simplest form is illustrated comprising two carbon-carrying blades 28 mounted on blocks 29 tied together by a connecting piece 30. The carbon-carrying blades are detachably fastened thereto in a manner as shown in Figure 6, in which the carbon-blades are provided with two downwardly-extending pins 38 engaging with holes 31 in the carbon-carrier. The carbon-carrier blades used with the auxiliary carbon-carriers are the same as used in the regular machine, and comprise a supporting blade 32 and a locking blade 33, the latter being pivotally mounted on a finger-piece 34. The four-blade auxiliary carbon-carrier is illustrated in Figure 5, and comprises two end blocks 35 and a connecting piece 36. The blocks 35 are provided with the downwardly-extending pins 26, engaging with the holes 27 in the blocks 37 of the carrier 25, and extend to the rear forming a higher step 39 disposed to carry a second set of carbon-carrying blades. Said blocks 35 are wider than the blocks 37, and are hollowed, as indicated in Figure 6 by the numeral 40, for the purpose of clearing the steps 41 of the blocks 37. The six-blade auxiliary carrier, shown in Figure 5, is the same as the four-blade carrier previously described, with the exception of a third step 42 provided to carry the extra blades 22 detachably mounted thereon. It will be noted that in Figure 1 the same auxiliary carbon-carriers are shown, and are disposed relatively to the regular carrier in the same manner as illustrated in Figure 5, and that in Figure 2 the same auxiliary carbon-carriers are shown, but are differently disposed in relation to the regular carrier.

In another form of this invention the auxiliary carbon-carriers are mounted at the rear of the regular carrier, and the modification is illustrated in Figures 3 and 4. Said auxiliary carriers comprise a horizontally-disposed cross-bar 44 having two downwardly-extending supporting extensions 45, one at each end, and said extensions terminating in a fork having two prongs 46, designed to be snapped over the screws 47, normally holding the side gages 48, and into which a groove 49 is cut to receive the supporting extensions. At both ends of the cross-bar 44 there are provided blocks 54 designed to receive the carbon-carrying blades 50 shown in Figure 3. Said blades are provided with the usual pins which enter the holes 51. It will be noted that the screws 47, supporting this type of auxiliary carrier, are made special and substitute the

regular screws 52, shown in Figures 1 and 2.

Variations may be resorted to within the scope of the invention, and portions of the improvements may be used without others.

5. Having thus described my invention, I claim:

1. In a machine for typing upon work-webs, the combination with a platen, of a carbon-carrier common to a plurality of superposed sets of work-webs, said carbon-carrier including supports adjacent the sides thereof, and a series of bridge-devices spanning said supports and arranged in ascending order one behind the other, each 10 of said bridge-devices carrying a group of carbon-holding blades for interleavement with the plies of a set of work-webs, said bridge-devices forming with their associated groups of carbon-holding blades independently 15 detachable units.

2. In a machine for typing upon work-webs, the combination with a platen, of a carbon-carrier common to a plurality of superposed sets of work-webs, said carbon-carrier including supports adjacent the sides thereof, and a series of bridge-devices spanning said supports and arranged in ascending order one behind the other, each of said bridge-devices carrying a group of carbon-holding blades for interleavement with the plies of a set of work-webs, said bridge-devices forming with their associated groups of carbon-holding blades independently 20 detachable units, and being of varying blade-carrying capacities, whereby the independent web-sets may vary as to the number of 25 work-plies composing the sets.

3. In a machine for typing upon work-webs, the combination with a platen, of a carbon-carrier common to a plurality of superposed sets of work-webs, said carbon-carrier including supports adjacent the sides thereof, and a series of bridge-devices spanning said supports and arranged in ascending order one behind the other, each of said bridge-devices carrying a group of carbon-holding blades for interleavement with the plies of a set of work-webs, said bridge-devices forming with their associated groups of carbon-holding blades independently 40 detachable units, said carbon-holding blades being independently detachable from their associated bridge-devices.

4. In a continuous billing typewriting machine having a carriage, an extension, a platen on said carriage around which work-webs interleaved with carbon-sheets may be fed, and a truck on said extension, the combination with step-shaped supports adjacent the sides of said truck, of a plurality of individual blade-carrying frames interchangeably positionable upon the steps, the carbon-sheets being attached to the blades, pin-and-socket connections between the frames and 55 the supports, an individual blade-carrying

frame extending adjacent the rear of said supports and beyond the first-named frames, and means, independent of said steps, for supporting the last-named frame on said truck.

5. In a continuous billing typewriting machine having a carriage, an extension, a platen on said carriage around which work-webs interleaved with carbon-sheets may be fed, and a truck to move on said extension, to and away from the platen, the combination with step-shaped supports adjacent the sides of said truck, of a plurality of individual blade-carrying frames interchangeably positionable upon the steps, the carbon-sheets being attached to the blades, pin-and-socket connections between the frames and the supports, side gages at the rear of said support, including fastening means therefor, an individual blade-carrying frame extending adjacent the rear of said supports and in stepped relation beyond the first-named frames, and attachment clips carried by the rearwardly-extending frame, said clips being detachably secured to the truck by the side-gage-fastening means.

6. In a continuous billing typewriting machine, the combination with a carriage and a platen on said carriage around which a web comprising individual plies of work-sheets with interleaved carbon-sheets may be fed, of a carbon-carrier associated with said web, side gages for said web, devices to hold said gages in adjusted positions on said carbon-carrier, and a second carbon-carrier supported on the gage-holding devices.

7. In a continuous billing typewriting machine, the combination with a carriage and a platen on said carriage around which a web comprising individual plies of work-sheets with interleaved carbon-sheets may be fed, of a carbon-carrier associated with said web, side gages for said web, screws to hold said side gages in adjusted positions on said carbon-carrier, said screws having annular grooves, a second carbon-carrier, and arms on said second-named carbon-carrier to engage in the grooves of said screws to support the last-named carbon-carrier on the first-named carbon-carrier.

8. In a continuous billing typewriting machine, the combination with a carriage and a platen on said carriage around which a web comprising individual plies of work-sheets with interleaved carbon-sheets may be fed, of a carbon-carrier associated with said web, a second carbon-carrier, means comprising a stud on one of said carbon-carriers, and means comprising a bifurcated arm to form resilient fingers on the other carbon-carrier to detachably mount and hold the second-named carbon-carrier on the first-named carbon-carrier.

9. In a machine of the class described having a platen, an extension and a carbon-

carrying truck mounted on said extension, the combination with step-shaped supports at each side of the truck, of individual carbon-blade-carrying frames arranged to be 5 detachably secured to any of the steps, the frames each including a pair of oppositely-disposed step-shaped blocks upon which the carbon-blades are carried, some of the blocks being recessed so as to fit upon a series of 10 the support steps, and a bar connecting the blocks.

10. In a continuous billing typewriting machine having a revoluble platen around which work-webs interleaved with carbon-sheets may be fed, an extension at the rear 15 of the machine, and a carbon-carrying truck mounted on said extension, the combination with supports adjacent each side of said truck, of a plurality of individually attachable and detachable carbon-blade-carrying 20 frames interchangeably positionable upon said supports, and means for increasing the capacity of the machine by increasing the number of frames on said truck, including 25 an extra frame overhanging the truck at the rear of said supports, and means for detachably securing said extra frame in such position.

11. In a continuous billing typewriting 30 machine comprising a revoluble platen mounted on a displaceable swing-frame, a movable carriage to support said swing-frame, feed-rolls co-operating with said platen to feed a work-web therearound, a 35 frame at the rear of the machine, a carbon-carriage operatively mounted on said frame disposed to travel towards and away from said carriage, a block on each side of said carbon-carriage and fast thereto for supporting a plurality of staggered carbon-carrying blades, and means attachable to 40 said blocks on the carbon-carriage instead of the carbon-carrying blades, to increase the capacity of the machine by increasing 45 the number of carbon-carrying blades on said carbon-carriage, said means comprising a plurality of adapter-frames comprising means for fastening the adapter-frames to the blocks on the carbon-carriage and means 50 for receiving and holding a plurality of carbon-carrying blades.

12. In a continuous billing typewriting 55 machine comprising a revoluble platen mounted on a displaceable swing-frame, a movable carriage to support said swing-frame, feed-rolls co-operating with said platen to feed a work-web therearound, a 60 frame at the rear of the machine, a carbon-carriage operatively mounted on said frame disposed to travel towards and away from said carriage, a block on each side of said carbon-carriage and fast thereto for supporting a plurality of staggered carbon-carrying blades, and means attachable to said 65 blocks on the carbon-carriage instead of the

carbon-carrying blades, to increase the capacity of the machine by increasing the number of carbon-carrying blades on said carbon-carriage, said means including a cross-bar having split pins disposed to engage holes in said blocks, and a plurality of holes for receiving and holding a plurality of carbon-carrying blades. 70

13. In a continuous billing typewriting machine including a revoluble platen, feed-rolls co-operating with said platen for line-spacing a work-web therearound, means including a carriage and a rear extension thereof for displacing interleaved carbon-sheets into a fresh section of the web, said 80 means comprising a carbon-carriage operatively mounted on said extension and disposed to be moved towards and away from said platen, said carbon-carriage comprising two side blocks and carbon-carrying blades 85 fast thereto for supporting a plurality of sheets of carbon-paper interleaving the work-web, side gages fast to said side blocks by means of screws for laterally guiding the web, and means detachably mounted on 90 said screws for increasing the number of carbon-carrying blades that may be used on the machine.

14. In a continuous billing typewriting 95 machine, including a revoluble platen, feed-rolls co-operating with said platen for line-spacing a work-web therearound, means including a carriage and a rear extension thereof for displacing interleaved carbon-sheets into a fresh section of the web, said 100 means comprising a carbon-carriage operatively mounted on said extension and disposed to be moved towards and away from said platen, said carbon-carriage comprising two side blocks and carbon-carrying blades 105 fast thereto for supporting a plurality of sheets of carbon-paper interleaving the work-web, side gages fast to said side blocks by means of screws for laterally guiding the web, and means detachably mounted on said 110 screws for increasing the number of carbon-carrying blades that may be used on the machine, said last-mentioned means including a cross-bar having two downwardly-extending supporting members engaging with 115 grooves in the body of said screws, blocks at the ends of said cross-bar fast thereto, and holes in said blocks for receiving and holding a plurality of carbon-carrying blades.

15. In a machine for typing upon work-webs, the combination with a platen and a truck movable toward and away from the platen, said truck including step-shaped supports adjacent its opposite sides, of a series of bridge-devices detachably mounted 120 one behind the other on the steps of said supports, each bridge-device carrying a 125 group of carbon-holding blades and forming therewith a unit detachable independently of the other blade-carrying bridge-devices, 130

each unit having the carbon-blades thereof interleaved with the plies of an independent set of work-webs.

16. In a machine for typing upon work-webs, the combination with a platen and a truck movable toward and away from the platen, said truck including step-shaped supports adjacent its opposite sides, of a series of bridge-devices detachably mounted one behind the other on the steps of said supports, said bridge-devices including step-shaped blocks detachably secured upon the steps of the supports, a cross-bar connecting said blocks, and carbon-carrying blades detachably mounted upon said blocks and forming therewith independent units, said blocks varying as to the number of steps composing the same, whereby different numbers or groups of carbon-holding blades are carried by each bridge-device so as to provide carbon-holding means for several sets of work-webs which vary as to the number of plies composing the same, said step-shaped blocks being attachable to any of the steps of said supports.

17. In a machine for typing upon work-webs, the combination with a platen and a truck movable toward and away from the platen, said truck including step-shaped supports adjacent its opposite sides, of a series of bridge-devices detachably mounted one behind the other on the steps of said supports, said bridge-devices including step-shaped blocks detachably secured upon the steps of the supports, a cross-bar connecting said blocks, and carbon-carrying blades detachably mounted upon said blocks and forming therewith independent units, said blocks varying as to the number of steps composing the same, whereby different numbers or groups of carbon-holding blades are carried by each bridge-device, so as to provide carbon-holding means for several sets of work-webs which vary as to the number of plies composing the same.

18. In a machine for typing upon work-webs, the combination with a platen and a

truck movable toward and away from the platen, said truck including step-shaped supports adjacent its opposite sides, of a series of bridge-devices detachably mounted one behind the other on the steps of said supports, said bridge-devices including step-shaped blocks detachably secured upon the steps of the supports, a cross-bar connecting said blocks, and carbon-carrying blades detachably mounted upon said blocks and forming therewith independent units, said blocks varying as to the number of steps composing the same, whereby different numbers or groups of carbon-holding blades are carried by each bridge-device so as to provide carbon-holding means for several sets of work-webs which vary as to the number of plies composing the same, said step-shaped blocks being attachable to any of the steps of said supports.

19. In a machine for typing upon work-webs, the combination with a platen and a carbon-carrier movable toward and away from the platen and including a full set of regular carbon-holding blades for interleaving with the plies of the work-webs, of an auxiliary carbon-blade-carrying device detachably mountable on said carbon-carrier to increase the capacity of the regular blades.

20. In a machine for typing upon work-webs, the combination with a platen and a carbon-carrier movable toward and away from the platen and including a full set of regular carbon-holding blades for interleaving with the plies of the work-webs, of means for increasing the carbon-holding capacity of said set, said means including a bridge-device carrying carbon-holding blades, and releasable clip-devices for attaching the blade-carrying bridge-device to the carbon-carrier.

JOHN WALDHEIM.
